ATTORNEY

UNITED STATES PATENT OFFICE

120,245

DESIGN FOR A GRIDDE SCRAPER

Beverly Osborne, Oklahoma City, Okla.

Application August 4, 1939, Serial No. 86,462

Term of patent 3½ years

To all whom it may concern:

Be it known that I, Beverly Osborne, a citizen of the United States, residing at Oklahoma City, in the county of Oklahoma and State of Oklahoma, have invented a new, original, and ornamental Design for a Griddle Scraper, of which the following is a specification, reference being had to the accompanying drawing, forming a part thereof.

I claim:

The ornamental design for a griddle scraper, as shown.

BEVERLY OSBORNE.
